UNITED STATES PATENT OFFICE.

WARREN A. BALL, OF SALEM, OHIO

SANITARY RECEPTACLE.

1,078,604.

Specification of Letters Patent. Patented Nov. 18, 1913.

Application filed September 19, 1911. Serial No. 650,274.

To all whom it may concern:

Be it known that I, WARREN A. BALL, a citizen of the United States, residing at Salem, in the county of Columbiana and State of Ohio, have invented a new and useful Improvement in Sanitary Receptacles, of which the following is a specification.

My invention relates to that class of sanitary receptacles in which a receptacle is provided and to the bottom or lower portion of which is pivotally attached a releasing cup.

The objects of the present invention are, first, to provide a sanitary receptacle or dispensing can that is simple in construction and easy of operation, and second, to provide means whereby the liquid is retained in the receptacle by a liquid seal, except at such times as it is desired to permit the flow of liquid from the receptacle. These objects together with other objects, readily apparent to those skilled in the art I attain by the construction illustrated in the accompanying drawings, although my invention may be embodied in a variety of other mechanical forms, the construction illustrated being chosen by way of example.

In the accompanying drawing: Figure 1 is a perspective view showing the device properly connected to a retaining yoke. Fig. 2 is an edge view showing parts in section. Fig. 3 is a side elevation showing the lower portion in section.

Similar numerals of reference indicate corresponding parts in all the figures of the drawing.

In the accompanying drawing, 1 represents the receptacle proper which may be formed of any size, reference being had to convenience and purpose. The lower portion of the receptacle is provided with the reduced extending portion 2, to which lower extended portion is pivotally attached the releasing cup 3, which releasing cup is provided with the knob or handle 4. The releasing cup 3 is also provided with the delivery spout or nozzle 5, which is normally located under the lip 6 and in close proximity therewith, except at such times as it is desired to release a portion of all of the liquid contained in the receptacle 1. The delivery cup 3 is pivotally connected to the extended portion 2 by means of the cross bolt 7, which cross bolt is provided with the nut 8. The extending portion 2 is formed hollow and is preferably provided with the integral sleeve 9, through which sleeve the bolt 7 is

passed as best illustrated in Fig. 2. The knob or handle 4 should be of such relative weight with reference to the releasing cup and its pivotal point that it will normally hold the releasing cup in the position illustrated in Fig. 1, and in full lines Fig. 3.

In use the receptacle 1 is filled or partially filled with liquid by inverting the receptacle from the positions illustrated in the drawings after which the receptacle is placed in the position illustrated in the drawings. A portion of the liquid contained in the receptacle 1 will find its way into the releasing cup 3 and when the cup is in the position illustrated in Figs. 1 and 2 a liquid seal is produced as between the liquid contained in the cup and the receptacle, owing to the fact that no air is permitted to enter said receptacle, except through the open end of the extended portion 2 by which arrangement no liquid will pass or escape from the receptacle, owing to the liquid seal as between the liquid contained in the receptacle 1 and the pivoted releasing cup 3.

When it is desired to release a quantity of liquid the knob or handle 4 is lifted upward by the hand, thereby lowering the spout or nozzle 5 and removing such spout or nozzle from the lip 6 at which time liquid will flow from the cup 3, until the releasing cup 3 is permitted to assume the position shown in Fig. 1 and when in that position the flow of liquid is cut off.

For the purpose of suspending the receptacle a yoke 9^a is provided, which yoke may be attached to any desired object, such as a barber's chair.

For the purpose of adjusting the yoke so as to bring the receptacle 1 into a true vertical position or into an inclined position as desired, the yoke is provided with the elongated slot 10, through which elongated slot one of the retaining screws or its equivalent is passed, and a similar retaining screw or its equivalent passed through the aperture 11 by which arrangement the yoke can be adjusted at any desired angle within its movement.

For the purpose of providing means for suspending the receptacle 1, said receptacle is provided with the lugs 12, which lugs are seated in the aperture 13 and the recess 14, said last mentioned aperture and recess being formed in the yoke 9. The object of locating one of the hinges 12 in the recess 14 is to provide means for easily detaching

the receptacle 1 from the yoke without necessitating the removal of the yoke from the object to which it is attached.

Having fully described my invention what 5 I claim as new and desire to secure by Letters Patent, is—

1. The combination with a portable sanitary receptacle which has a reduced extension and is open only at the end of said extension, of a releasing cup having side walls which are pivoted to the side walls of said extensions, the releasing cup conforming in shape to the extension which it closely overlies on all sides and being constructed and proportioned to project from its pivot in a normal position wherein it closes the outer end of said extension against the escape of the liquid contents of said receptacle.
2. The combination with a portable sanitary receptacle which has a reduced extension and is open only at the end of said ex-

tension, the latter having a projecting lip, of a releasing cup having side walls which are pivoted to the side walls of said extension and having also a spout lying adjacent 25 the lip, and a projecting handle at the end thereof opposite the spout, the releasing cup conforming in shape to the extension which it closely overlies on all sides and being arranged to project from its pivot in a normal 30 position of stable equilibrium wherein it closes the outer end of said extension against the escape of the liquid contents of said receptacle.

In testimony that I claim the above, I have 35 hereunto subscribed my name in the presence of two witnesses.

WARREN A. BALL.
